(57) CLAIM

The ornamental design for a radio receiver, as shown.

DESCRIPTION

The claimed radio receiver is used for receiving sound broadcast. It could perform auto-turning function by pressing once a button on it and could be clip-on to clothes or to another article.

FIG. 1 is a front elevational view of a radio receiver showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
